Specification for Design.

Patented Mar. 27, 1917.

Application filed January 20, 1917. Serial No. 143,523. Term of patent 7 years.

To all whom it may concern:

Be it known that we, ROBERT Y. BARROWS, a citizen of the United States of America, residing in the town of Rutherford, in the county of Bergen and State of New Jersey, and GEORGE V. STRAHAN, a citizen of the United States of America, residing in the city of Newark, in the county of Essex and State of New Jersey, have invented a new, original, and ornamental Design for a Ceiling-Canopy for Lighting-Fixtures, of which the following description, in connection with the accompanying drawings, is a specification.

Figure 1 of the drawings is a plan view of the underside of a ceiling canopy for lighting fixtures, showing our new design; and Fig. 2 is an elevation of the ceiling canopy of Fig. 1. The design for the ceiling canopy is symmetrical but is omitted from the left half of each figure.

We claim as our invention:

The ornamental design for a ceiling canopy for lighting fixtures, as shown.

ROBERT Y. BARROWS.
GEORGE V. STRAHAN.
